UNITED STATES PATENT OFFICE.

JULIUS BRENZINGER, OF FAIRFIELD, AND PAUL H. LANGE, OF BRIDGEPORT, CONNECTICUT, ASSIGNORS TO THE MAX AMS MACHINE COMPANY, OF BRIDGEPORT, CONNECTICUT, A CORPORATION OF NEW YORK.

HEADING MACHINE AND BODY-CONVEYING MEANS.

Application filed November 22, 1922. Serial No. 602,505.

This invention relates to means for feeding bodies to, through, and from heading or other machines for acting on bodies or the contents thereof.

5 Plants for packing bodies are generally provided with body forming machines, filling machines and heading or seaming machines and the object of the present invention is to coordinate in a simple and effective 10 manner a heading machine with transportation or conveying means leading from a body forming or filling machine to the heading machine and from the latter to a delivery point or to some other machine.

15 In accordance with the above, the invention consists of the hereinafter described features of construction, combination of elements and arrangement of parts, a preferred form of which is disclosed in the accompanying 20 drawings in which:

Fig. 1 is a front elevation of a heading machine and associated parts embodying the invention.

Fig. 2 is a horizontal sectional plan view 25 on the plane of line 2—2 of Fig. 1.

Fig. 3 is a vertical transverse sectional view on an enlarged scale on the plane of line 3—3 of Figs. 1 and 2.

Fig. 4 is a vertical longitudinal sectional 30 view on an enlarged scale on the plane of irregular line 4—4 of Fig. 3.

Fig. 5 is a view in elevation, partly in section of the body reversing device.

Fig. 6 is a vertical transverse sectional 35 view on an enlarged scale on the plane of irregular line 6—6 of Fig. 2.

Fig. 7 is a vertical transverse sectional view on an enlarged scale on the plane of line 7—7 of Figs. 1 and 10.

40 Fig. 8 is a vertical transverse view on an enlarged scale on the plane of line 8—8 of Fig. 1.

Fig. 9 is a detail sectional view on the plane of line 9—9 of Fig. 7.

45 Fig. 10 is an enlarged fragmentary view partly in front elevation and partly in section of the discharge end of the machine.

1 indicates a rotatable turret, in this in-

stance intermittently operated, having a series of pockets 2 or other means for advancing the bodies in an orbit through the machine. 3 is a table on which the bodies slide as they are advanced by the turret means. 4 is an in-feed means and 5 is an out-feed means for the bodies. 6 is an up-ending device and 7 a transfer device for moving the bodies from the up-ending device to the turret means. Viewing these elements in plan, as in Fig. 2, it will be understood that a container or body 8 is fed into the machine by means of in-feeding device 4 in a recumbent position, is up-ended by device 6, is transferred by device 7 to a pocket 2 of the turret, is carried through the machine in an orbit, sliding over the table in so doing, and passing one or more stations at which work is performed on the body or container, a station of this character being indicated at the seaming station 9, and is then brought into alignment with the out-feed means 5, said body being removed from the turret by a discharge means 10. At the point indicated at 11 there may be a detector located which also acts as an ejector, but this arrangement and the construction 75 of the detector and ejector are not covered in this application being the subject matter of a separate application, Ser. No. 602,506 filed November 22, 1922.

In the present instance the infeeding 80 means take the following form. 12 indicates a framework in which is mounted a reciprocating member 13 carrying spring pressed feeding pawls 14 that engage bodies 8 on their stroke to the right (Fig. 4) 85 and which pass beneath the bodies on their stroke to the left (Fig. 4) being depressed by said bodies. 15 indicates spring pressed holding pawls, mounted on frame 12, that hold the bodies during the return stroke of 90 the feeding pawls and are raised during the forward movement of the bodies. Said bodies are here shown as being of elongated shape and occupy a recumbent position. Motion for reciprocating member 13 is here 95 derived from crank disc 16 and three con-

nections 17, 18 and 19 (Fig. 1), lever 18 being pivotally supported at 20 on frame 12.

The up-ending means (Figs. 3, 4 and 5) are constructed as follows: 21 indicates a spider mounted on spindle 22 and projecting up through an opening in table 3. This spider consists of a cross-shaped body member 23 having four pairs of sheet metal cheeks or plates, one plate 24 of each pair 10 constituting a receiving surface for receiving recumbent body 8 and another plate 25 constituting an abutment member against which the end of the can body is fed. Member 25 carries a retaining surface 26 which 15 is adjustably mounted and is secured in position by nut and screw 27. Suitable means are provided for intermittently rotating the spider step by step in one direction only. In this case shaft 22 is provided with a star 20 wheel 28 with which engage pins 29 on shaft 30 which latter is a continuously rotating member carrying a gear 31 driven by pinion 32 on shaft 33 actuated by sprocket 34. Spider 21 is in the position indicated 25 in Figs. 3, 4 and 5 when receiving a body, said body passing in between receiving surface 24 and retaining surface 26. The spider is now given a quarter turn thereby up-ending the body causing its lower end to 30 be supported by abutment surface 25 and placing it in line with one of the pockets of the turret.

Suitable means are provided for moving the container or body from between the receiving surface 24 and retaining surface 26 and at right angles to the in-feeding movement of 4. In this instance the parts take the following form: 35 is a bushing in which slides a plunger 36, the head 37 of which, 40 upon the inward movement of said plunger, comes in contact with the body and pushes it out of the up-ending device and into one of the pockets of the turret. The means for reciprocating the plunger consist here of a 45 strap cam 38 (Fig. 2), rod 39, crank lever 40, rockshaft 41 and link 42.

In the present instance the outfeed means comprise a belt 43 driven by means of chain 44 actuated by sprocket 45, said chain passing over sprocket 46 at its other end (Figs. 1, 2 and 8) and also comprise a discharge device 10 (Fig. 10) here constructed as follows: 47 is a guide (Figs. 7 and 10) in which is mounted a reciprocating member 48 carrying an upright member 49 provided with discharge fingers 50 which project above and below pocket 2. Connected to slide 48 is a rod 51 which is adjustably secured to arm 52 on rockshaft 53, said rockshaft having another arm 54 pivotally supporting connection 55. Said connection carries a bushing 56 into which extends crank roller 57 on crank disc 58 which crank disc is carried by shaft 59. It will now be understood that

rotation of the crank disc causes reciprocation of member 48 which acts to move a body out of pocket 2 and that this process continues until one body pushes another body over on belt 43. In order to insure that the body will extend above pocket 2, table 3 is provided with a ramp 60 over which the body travels and which causes it to rise.

The seaming station 9 has already been indicated. Below this seaming station is the usual pedestal 61 (Fig. 6) into which the body 8 slides when moved by pocket 2. Any suitable means may be used to raise and lower this pedestal. In this instance (Fig. 9) a cam 62 is used mounted on shaft 63 and this cam actuates rocking lever 64 connected by links 65 to yoke 66. This yoke is adjustable on stem 67 by turning bushing 68 in threaded engagement with stem 67 in a manner well understood. The result of such adjustment is to vary the initial position of said pedestal without varying the amount of vertical movement of the pedestal, and to retain different sizes of bodies in the same relation with the seaming mechanism (not shown). Adjacent the seaming station is the shaping and holding member 69 (Fig. 6) which is complementary to pocket 2 and is carried by reciprocating member 70 actuated by cam 71, lever 72 pivoted at 73 and adjustably connected by means of rod 74 and elements associated therewith said rod being pivotally connected at 75 to member 70.

Power is applied by means of belt 76 (Fig. 1) to shaft 77 which latter carries a gear 78 meshing with gear 79 on upright shaft 80. Upright shaft 80 carries a worm 81 (Fig. 6) meshing with worm wheel 82 on shaft 83 (Figs. 2 and 6). This shaft 83 carries strap cam 48 from whence motion is transmitted to the transferring device 7. It also carries bevel gear 84 which meshes with bevel gear 85 on shaft 63 (Fig. 7). As previously explained shaft 63 carries cam 62 for actuating the pedestal. Shaft 63 also carries a bevel gear 86 meshing with bevel gear 87 on upright shaft 88. This upright shaft 88 (Fig. 10) carries a pin 89 meshing with slotted member 90 thereby imparting an intermittent progressive motion to same. Connected to member 90 is gear 91 and this latter meshes with gear 92 carried by pedestal 1. Shaft 63 (Fig. 7) also carries a gear 93 meshing with gear 94 (Fig. 8) thereby driving shaft 59 and shaft 59 carries a pinion 95 from which power is transmitted to sprocket 45 by means of gears 96 and 97 (Figs. 1 and 8). Gears 96 and 97 as well as sprocket 45 are carried by a bracket 98 adjustably mounted on shaft 59 (that is center of pinion 95) and said bracket is provided with a stem 99 extending into curved slot 100 in bracket 101 and secured in any ad-

justed position by means of nut 102. By these means the distance between sprockets 45 and 46 is varied (Fig. 1). Shaft 59 also carries two sprockets 103 and 104 and from 5 sprocket 103 extends a sprocket chain 105 to sprocket 106 of crank disc 16 (Figs. 1, 3 and 4), while another chain 107 extends from sprocket 104 to sprocket 34 of the up-ending devices (Figs. 1, 3 and 4). Sprocket 34 is carried 10 by a bracket 108 hung on the shaft 30 of gear 31 and a curved guide and bolt 109 is used to fasten this bracket in the position to which it has been adjusted. By these means the distance between sprockets 34 and 15 104 can be varied.

The reason for these adjustable driving connections are as follows: As will be recalled the throw of cam 62 (Fig. 9) for actuating the pedestal is constant, but the initial position of the pedestal 61 (Fig. 6) is adjusted as previously described to suit varying heights of bodies. This adjustment renders it necessary to adjust table 3 so that body 8 may move smoothly from the table 20 to the pedestal and back again. This in turn renders it desirable to adjust the infeed, outfeed, up-ending, transferring and discharge mechanisms and to adjust their driving connections. This is accomplished in the 25 following manner. Table 3 is carried by a vertical slide 110 (Fig. 4) moving in guideways 111. As will be seen this slide carries the up-ending device and its driving means from the point of the adjustable sprocket 34. It also carries by means of bracket 112 30 (Figs. 1 and 3) the transfer device, this bracket being bolted to slide 110, or to a member connected therewith, by means of bolts 113 (Fig. 1). So likewise crank disc 16 for actuating the infeed is carried by slide 40 110, and so is sprocket 106 (Fig. 3). Infeed bracket 12 (Fig. 4) is bolted at 114 to slide 110 or to the casting 115 carrying table 3. Outfeed carriage 116 (Figs. 8 and 10) is 45 bolted at 117 to the casting 115 of table 3 and is therefore carried by slide 110, said carriage 116 also supporting rockshaft 53 of the discharging device. Bracket 116 also carries bracket 119 adjustably bolted to it 50 at 120 for immediately supporting the belt. Sprocket 45, shaft 59 and bracket 98 are also connected with carriage 116 and slide 110. Brackets 12 and 119 are connected by adjustable stays 121 (Fig. 1) to the base plate 55 of the machine. These stays are pivotally connected at their upper and lower ends as shown. It will now be understood that by raising and lowering slide 110 not only will table 3 be adjusted but so also will the infeed, up-ending, transferring, discharging 60 and out-feeding mechanisms, and further that suitable adjustment of the driving connections may be made to compensate for such adjustment.

Any suitable means may of course be used

to raise or lower slide 110. In the present instance (Figs. 1, 7 and 10) slide 110 is provided with a bushing 122 to which is pinned threaded stem 123 which latter passes through nut 124 carried by handwheel 125 and resting on upright 126. By turning handwheel 125 and thereby nut 124 it will be evident that slide 110 will be raised or lowered at the will of the operator.

We claim:

1. Body conveying mechanism comprising: a rotatable member, means for feeding a body occupying a recumbent position, a member for moving the body into an upright position, means for intermittently and progressively rotating said second member in one direction only, and means for moving the up-ended body to the first member.

2. Body conveying mechanism comprising: a rotatable member, means for feeding a body occupying a recumbent position, a spider to receive the recumbent body, and actuating means to intermittently and progressively rotate said spider step by step in one direction only to up-end said body, and means for moving said up-ended body to the rotatable member.

3. Body conveying mechanism comprising: a rotatable member, means for feeding a body occupying a recumbent position, a spider to receive the body in a recumbent position, a continuously rotating member, a pin-and-slot connection between the continuously rotating member and the spider to thereby up-end said body, and means for moving said up-ended body to the first member.

4. An up-ending device for bodies comprising: a spider having a receiving surface, adapted to receive a body occupying a recumbent position, an abutment surface against which the end of the body abuts and a clamping surface substantially parallel to the receiving surface, and actuating means for the spider to intermittently and progressively rotate said spider step-by-step in one direction only.

5. An up-ending device for bodies comprising: a spider having a receiving surface, adapted to receive a body occupying a recumbent position, an abutment surface against which the end of the body abuts and a clamping surface substantially parallel to the receiving surface, actuating means for the spider to intermittently and progressively rotate said spider step-by-step in one direction only, and means for pushing the body out from between the receiving and clamping surfaces in a direction at right angles to its advancing movement into the spider.

6. A heading machine comprising: a rotatable turret having means for moving bodies in an orbit through the machine, a table adjacent said turret on which the

bodies slide as they are moved by the turret means, means for raising and lowering the table, body in-feeding means, body up-ending means, and a body transfer means all 5 adjustable with the table.

7. A heading machine comprising: a rotatable turret having means for moving bodies in an orbit through the machine, a table adjacent said turret on which the 10 bodies slide as they are moved by the turret means, means for raising and lowering the table, body in-feeding means, body up-ending means, body transfer means and body discharge means all adjustable with the 15 table.

8. A heading machine comprising: a rotatable turret having means for moving bodies in an orbit through the machine, a table adjacent said turret on which the 20 bodies slide as they are moved by the turret means, means for raising and lowering the table, body in-feeding means, body up-ending means, body transfer means, body discharge means, and body out-feed means all 25 adjustable with the table.

9. A heading machine comprising: a rotatable turret having means for moving bodies in an orbit through the machine, a table adjacent said turret on which the 30 bodies slide as they are moved by the turret means, means for raising and lowering the table, a pedestal extending up through said table, means for adjusting the initial position of the pedestal to accord with the height 35 of the table, and can feeding and delivery means adjustable with the table.

10. Body conveying mechanism comprising: a table, means for adjusting the table vertically, a carriage adjustable with the 40 table, a reciprocating body feeding member sliding in the carriage, means for reciprocating the carriage adjustable with the table, a body up-ending means carried by the table, means for actuating said body up-ending 45 means adjustable with the table, and adjustable driving connections from a fixed point for imparting motion to the means for reciprocating the carriage and to the means for actuating the body up-ending means.

11. Body conveying means comprising: a table, means for adjusting the table vertically, a rotatable turret having means for moving bodies over the table, an out-feed mechanism adjustable with the table, a discharge 55 means for moving bodies out of the turret, means also adjustable with the table, and adjustable actuating means for driving the discharge and out-feed means notwithstanding adjustments of the table.

12. Body conveying means comprising: a table, means for adjusting the table vertically, a rotatable turret having means for moving bodies over the table, an out-feed mechanism adjustable with the table, a discharge 60 means for moving bodies out of the

turret, means also adjustable with the table, a shaft independent of the table, a rockshaft adjustable with the discharge means, a crank on the independent shaft, an adjustable connection between the crank and the rockshaft, 70 and an adjustable driving connection between the out-feed means and the independent shaft.

13. The combination of a transferer for containers, means to feed the containers to 75 the transferer successively while in horizontal position, means to move the transferer to raise the containers from a horizontal to an upright position, seaming mechanism, and means to successively push the containers 80 from the transferer to the seaming mechanism.

14. The combination of a transferer having means to receive containers in a horizontal position and having a stop for the 85 containers, conveyor means to successively present containers to the transferer in a horizontal position thereon, means to move the transferer from the container receiving position to a position to present the containers 90 in an upright position, seaming mechanism, and means to successively push the containers from the transferer toward the seaming mechanism.

15. The combination of a transferer, 95 means to feed containers step-by-step to the transferer, means to operate the transferer step-by-step for each container received to raise the container from a horizontal to an upright position, and means to push the containers 100 successively from the transferer, seaming mechanism associated with the transferer, and means to push the containers successively from the transferer toward the seaming mechanism.

16. The combination of a transferer having means to receive containers lying on their sides, means to rotate the transferer from a container receiving position to present the container in an upright position, 110 means to successively feed containers to the transferer, a pusher movably supported at one side of the transferer, an arm to operate the pusher, a cam operatively connected with said arm, and seaming mechanism having a 115 turret provided with receivers located on the side of the transferer opposite the pusher in position to receive containers from the transferer.

17. The method of applying closures to 120 containers consisting in feeding open-end containers successively in a horizontal position with their open ends horizontally disposed, turning said containers successively from a horizontal to an upright position 125 with their open ends located upwardly, moving the upright containers to position to receive closures, applying closures to said open ends of the containers, moving the containers and the closures successively in position 130

respecting closure seaming means, and securing said closures to said ends of the containers by said securing means.

18. The combination of a transferer having means to receive containers lying on their sides, means to rock the transferer from a container receiving position to present the container in an upright position and to rock the transferer to receive another container, means to successively feed con-

tainers to the transferer, means to push containers from the transferer, and seaming mechanism to receive containers from the transferer.

Signed at Bridgeport, in the county of 15
Fairfield and State of Connecticut, this 17th
day of November, 1922.

JULIUS BRENZINGER.
PAUL H. LANGE.
